UNITED STATES PATENT OFFICE.

VICTOR WILLOUGHBY, OF RIDGEWOOD, NEW JERSEY, ASSIGNOR TO AMERICAN CAR
AND FOUNDRY COMPANY, OF NEW YORK, N. Y., A CORPORATION OF NEW JERSEY

MINE CAR.

Application filed January 24, 1925. Serial No. 4,516.

To all whom it may concern:

Be it known that I, VICTOR WILLOUGHBY, residing at Ridgewood, Bergen County, New Jersey, and being a citizen of the United States, have invented certain new and useful Improvements in a Mine Car, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

20 Fig. 1 is a view showing the improved mine car principally in side elevation, one portion thereof being broken away and shown in longitudinal section;

25 Fig. 2 is a top plan view of the improved mine car with one corner portion broken away and one of the wheel hoods broken away;

Fig. 3 is a transverse sectional view taken along the line 3—3 of Fig. 2;

30 Fig. 4 is a fragmentary top plan view showing a modified form of wheel shield; and

Fig. 5 is a transverse sectional view taken along the line 5—5 of Fig. 4.

35 An object of this invention is to provide a mine car having an improved flooring or bottom formed of a plurality of sections which are of a special construction and secured together in an improved manner.

40 Another object of the invention is to so construct the mine car that the side slope sheets of the bottom may be firmly secured to the intermediate bottom section and braced against downward movement by the 45 wheel shields which are secured to the side slope sheets and extend in overlapping relation to the intermediate bottom section.

Another object of the invention is to so 50 construct this mine car that the journals for the axles may extend beneath the intermediate bottom section and be secured by fastener bolts which extend through the intermediate section and through the portions of the wheel hoods or shields which over-

lap the side portions of the intermediate 55 bottom section.

Another object of the invention is to provide a mine car in which the intermediate section may be formed of longitudinally disposed floor boards having a buffering 60 column disposed between certain of the floor boards and these floor boards and the buffering column secured in place by fasteners passing through cross ties extending beneath the flooring and having extended end portions which are secured to the side slope sheets and terminating in upwardly disposed portions forming posts for the side walls of the car.

This car is provided with a bottom or 70 flooring having an intermediate section and side sections. The intermediate section is formed of longitudinally extending floor boards 1 which are disposed upon opposite sides of the longitudinally extending buffering 75 column 2. This buffering column is formed of metal and is U-shaped in cross section and provided with outstanding side flanges 3 which extend beneath the adjacent floor boards and are secured to the floor boards by fasteners 4. These floor boards and the buffering column extend beyond the end walls 5 and the extended end portions of the floor boards and buffering column will be covered by a protecting jacket 6. If desired, the 85 draft gear may be mounted in the end portions of the buffering column.

The side walls 7 extend between the end walls 5 and are formed of wall boards 8 which are disposed one above the other as 90 shown in Figs. 1 and 3 and secured by fastener bolts 9 to the posts 10 which are formed on the upturned end portions of the cross ties 11. These cross ties 11 are formed of metal strips which extend beneath the intermediate floor or bottom section and are then extended upwardly as shown at 12 and along the under faces of the side slope sheets 13 as shown at 14 with their end portions bent to extend upwardly 100 and provide the wall posts 10. It will therefore be seen that the floor sections and the side walls will be firmly supported by these cross ties and the side walls prevented from bulging. The side slope sheets 13 are 105 formed of heavy sheet metal and have their outer side portions extending beneath the side walls and provided with upwardly ex-

tending flanges 15 which are secured against the outer faces of the side walls by the up-turned posts forming end portions of the cross ties. From an inspection of Fig. 3 5 it will be seen that these side slope sheets are held in close engagement with the side walls thereby providing a tight joint which will prevent fine material from sifting out of the car. The inner side portions of the 10 side slope sheets extend downwardly as shown at 16 for close contacting engagement with the side edge faces of the intermediate floor section and terminate in inwardly disposed side flanges 17 which extend beneath 15 the adjacent floor boards where they are secured by the fasteners 18 and 22 and also by the cross ties 11, the flanges 16 and 17 with the slope sheet adjacent thereto forming in effect supporting sills.

20 The axles 19 which carry the wheels 20 upon their end portions extend transversely beneath the car body and are mounted in journals 21 which extend beneath the intermediate floor section and said sills thereby 25 supporting the body portion of the car and are secured by fastener bolts 22. These fastener bolts 22 will securely hold the journals in place but will permit the journals to be easily and quickly removed when necessary. The car wheels 20 are of such size that the upper portions of the car wheels would 30 strike the side slope sheets 13 and therefore in order to accommodate the upper portions 35 of the wheels each of the side slope sheets will be provided either with openings 23 through which the wheels extend or these side slope sheets will be crimped upwardly as shown in Figs. 4 and 5 to provide pockets 40 24. It is necessary to close the openings 23 to prevent the material placed in the car from passing through these openings and therefore each of the openings 23 is covered by a hood 25 which is secured upon the upper 45 face of the side slope sheet by rivets or other suitable fasteners 26. These hoods have upwardly extending dome shaped portions which are disposed over the openings 23 and in spaced relation to the wheels as shown in Fig. 3 and each hood is further 50 provided with an extended base portion 27 which extends in overlapping relation to the adjacent floor boards of the intermediate floor section. These extended base portions 55 of the hoods are secured to the floor boards by fasteners 28 and are further secured by the fastener bolts 22 which in addition to passing through the floor boards also pass through these extended portions of the 60 hoods. When the form of pocket shown in Figs. 4 and 5 is made use of to receive the upwardly extending portions of the wheels it is not necessary to provide large hoods 65 shown in Figs. 1, 2 and 3 but it is necessary to provide a reinforcing cover in the form 70 of a small hood or protecting shield which

will prevent the pockets from being dented and moved into engagement with the wheels by heavy lumps of coal or other material thrown into the car. Therefore there has been provided protecting hoods or shielding strips 29 which extend transversely across the pockets 24 as shown in Fig. 4. These hoods or shields 29 are substantially of an inverted V-shape as shown in Fig. 5 and each has one end secured to the upper face 75 of the side slope sheet by the fasteners 30 and its other end portion extending in overlapping relation to the adjacent floor board of the intermediate floor section and secured by the fastener bolts 22. These strips will 80 effectively protect the pockets 24 and prevent them from being damaged by heavy material thrown into the car and further prevent injury to the car wheels which would be caused by the pockets being forced into vertical engagement with the flanges of the wheels.

What is claimed is:

1. In a mine car, a body having a bottom and side and end walls, said bottom comprising an intermediate section and side sheets having their outer side portions secured to the side walls and their inner side portions extending in underlying relation to the side portions of the intermediate bottom section, said side sheets having pockets adjacent the intermediate section and spaced from each other, axles extending transversely beneath the body and having their end portions disposed beneath the side sheets, wheels upon the end portions of said axles and extending upwardly into said pockets, and shields secured upon said side sheets and having upwardly arched portions disposed above said pockets and portions extending in overlapping relation to the intermediate bottom section, and fasteners securing the side sheets and shields to the side portions of the intermediate bottom section.

2. In a mine car, a body having a bottom and side and end walls, said bottom comprising an intermediate section and side sheets having their outer side portions flanged upwardly at the outer side of the side walls and their inner side portions extending in underlying relation to the side portions of the intermediate bottom section, axles extending transversely beneath said body and having their end portions disposed beneath said side sheets, wheels upon the end portions of said axles, shields or hoods secured upon the upper faces of said side sheets above said wheels and having portions extending in overlapping relation to the intermediate bottom section and fasteners securing the hoods and side sheets to the intermediate bottom sections.

3. In a mine car, a body having a bottom and side and end walls, said bottom comprising an intermediate section and side sheets having their outer side portions se-

- cured to the side walls and their inner side portions extending in underlying relation to the side portions of the intermediate bottom section, axles extending transversely beneath said body and having their end portions disposed beneath said side sheets, journals for said axles extending beneath the side portions of said intermediate bottom section and in crossed relation to the underlying inner side portions of said side sheets, wheels upon the end portions of said axles, the side sheets having pockets receiving the upper portions of said wheels, hoods secured to the upper faces of said side sheets and extending in overlying relation to the pockets and wheels and having portions overlapping the intermediate bottom section and fasteners passing through the intermediate bottom section and securing the journals and underlying and overlapping portions of the side sheets and hoods.
4. In a mine car, a body having a bottom and side and end walls, said bottom comprising an intermediate section of longitudinally disposed floor boards and side slope sheets between the intermediate section and side walls, said side slope sheets having their outer side portions extending beneath the side walls and provided with upstanding flanges secured against the outer faces of the side walls and their inner side portions provided with depending angular flanges engaging the side edges of the intermediate section and secured against the under face thereof, axles extending transversely beneath the car bottom with their ends beneath the side slope sheets and wheels upon the end portions of said axles and projecting upwardly into pockets provided in the side slope sheets, and hoods secured upon the upper faces of the side slope sheets and disposed above the wheels and having portions extending in overlapping relation to the intermediate bottom section and secured thereto.
5. In a mine car, a body having a bottom and side and end walls, said bottom comprising an intermediate section of longitudinally disposed floor boards and side slope sheets between the intermediate section and side walls, said side slope sheets having their outer side portions extending beneath the side walls and provided with upstanding flanges secured against the outer faces of the side walls and their inner side portions provided with depending angular flanges engaging the side edges of the intermediate section and secured against the under face thereof, axles extending transversely beneath the car bottom with their ends beneath the side slope sheets and wheels upon the end portions of said axles, and cross ties extending beneath the body and secured to the intermediate bottom section and side slope sheets and having their end portions extending upwardly and providing wall posts secured against the outer faces of the side walls.
6. In a mine car, a body having a bottom and side and end walls, said bottom comprising an intermediate section of longitudinally disposed floor boards and a buffering column between certain of said floor boards having side flanges secured against the under faces of adjacent floor boards, side slope sheets between the intermediate bottom section and side walls and having upstanding outer side flanges secured to the side walls and inner side flanges extending downwardly and inwardly against the side edges and under face of the intermediate section, axles extending transversely beneath said bottom and mounted in journals carried by the intermediate section, wheels carried by said axles beneath the side slope sheets, said side slope sheets having pocket receiving the upper portions of said wheels, wheel hoods secured upon the upper faces of said side slope sheets and in overlapping relation to the intermediate floor section and having upwardly extending portions disposed over the wheel receiving pockets, and cross ties extending transversely beneath the intermediate floor section and side slope sheets and secured thereto and having their end portions extended upwardly to provide posts for the side walls.
7. In a mine car, a body having a bottom and side and end walls, said bottom comprising an intermediate section formed of longitudinally disposed floor boards and a buffering column of an inverted U-shape in cross section disposed between certain of the floor boards intermediate the width of the said section and having its depending side walls provided with outstanding flanges secured against the under faces of the adjacent floor boards, side slope sheets disposed between the intermediate section and side walls and having their outer sides extending beneath the side walls and provided with upstanding flanges secured to the outer faces of the side walls, the inner side portions of said side slope sheets being bent to extend downwardly against the side edge faces of the intermediate section and terminating in flanges secured against the under face of the intermediate section, axles disposed transversely beneath said body and wheels carried by said axles beneath said side slope sheets, and shields secured to the side slope sheets and adjacent floor boards and having upwardly arched portions disposed over the wheels.

In witness whereof I have hereunto set my hand.

VICTOR WILLOUGHBY.
